UNITED STATES PATENT OFFICE

2,355,106

LUBRICATING COMPOSITION

Carl F. Prutton, East Cleveland, Ohio, assignor,
by mesne assignments, to The Lubri-Zol Development Corporation, Cleveland, Ohio, a corporation of Delaware

No Drawing. Application September 11, 1940,
Serial No. 356,357

11 Claims. (Cl. 252—48)

This invention relates, as indicated, to lubricants and more particularly to lubricating compositions capable of providing efficient lubrication under extreme pressure conditions, that is, of satisfactorily maintaining a lubricating film between bearing or other metallic surfaces operating under such extremely high pressures as would ordinarily cause seizing or scoring of such surfaces if a plain mineral lubricating oil, for example, were employed. These lubricating compositions are characterized by the fact that they are generally more effective and at the same time more stable than those used heretofore.

This application is a continuation in part of my copending application Serial No. 755,987, filed December 4, 1934, now Patent No. 2,320,984, dated June 1, 1943, and of my copending application Serial No. 121,827, filed Jan. 22, 1937, now Patent No. 2,242,260, dated May 20, 1941.

This invention further relates to a method of preventing seizing or scoring of relatively moving bearing surfaces and of reducing the wear or friction between such surfaces. The addition of certain agents to lubricating compositions generally for the purpose of improving their extreme pressure characteristics is not new. It is generally recognized that the degree of effectiveness of extreme pressure addition agents is usually directly proportional to their chemical or physico-chemical action on the bearing surfaces in producing a film which usually has an anti-fluxing function in preventing actual metal to metal contact, and in addition, sometimes the function of producing a film which is more strongly attached to the metal surfaces than plain lubricating oils. Also, the action of the addition agents is to provide a film characterized by the fact that the coefficient of friction between the surfaces where such film is maintained is generally lower than when ordinary lubricants are employed.

While a certain amount of chemical or physico-chemical action by the addition agent upon the bearing surfaces is necessary and desirable in order that an extreme pressure film may be produced, the addition agent must, nevertheless, be sufficiently stable and relatively inactive so that its activity along this line remains dormant under ordinary conditions and is only activated under the conditions of extreme pressure where its effectiveness is required for the stated purpose. In certain types of use, such as in crankcases of internal combustion engines, and in lubricants added to motor fuels and thus introduced into the apparatus to be lubricated through the combus-

tion zone, such relatively high temperatures are encountered that the resultant conditions tend to either decompose or render undesirably active many types of addition agents which are accordingly not usable in such an environment.

It is also generally accepted that many plain lubricating compositions such as refined mineral oil, due either to naturally occurring constituents in the base material or constituents in the finished product produced by refining processes, are relatively corrosive, particularly when used in conjunction with certain sensitive metals or alloys.

It is a principal object of this invention to provide a lubricating composition characterized by the fact that it contains an addition agent which may be effective not only for the purpose of imparting extreme pressure characteristics to the lubricant, but at the same time likewise effective as a corrosion inhibitor for certain active constituents which may either be originally present or added to the composition for certain specific results and which will otherwise be detrimentally active.

It is a further object of this invention to provide a lubricating composition which may be characterized by the fact that all of the above named desirable characteristics are imparted thereto by means of a single addition agent.

Other objects of this invention will appear as the description proceeds.

To the accomplishment of the foregoing and related ends, said invention then, consists of the features hereinafter fully described, and particularly pointed out in the claims, the following description setting forth in detail certain embodiments of the invention, these being illustrative, however, of but a few of the various ways in which the principle of the invention may be employed.

Broadly stated, this invention comprises the use as and in lubricants of organic compositions containing phosphorus and sulphur. These compositions are generally of the type which may be produced by reacting organic compositions with phosphorus and sulphur-containing reagents.

More specifically, this invention contemplates the use for the above purposes of organic compositions which (before reacting with the above referred to reagents) may desirably contain an organic oxygen compound and preferably a compound including a hydroxyl group which may advantageously be attached to a benzenoid ring structure.

Throughout the ensuing description of this

invention, the above described material indicated as usable either by itself as a lubricant or in minor amounts as an addition agent to other lubricating compositions for the purpose of improving the characteristics of the same will, for convenience, hereinafter be referred to as the addition agent.

As above indicated, the addition agent is of the type produced by reacting an organic composition with certain reagents which contain either separately in combined or elemental form, or in combination, phosphorus and sulphur. The addition agent thus produced may, in most cases, be described as an organic composition containing both the elements, phosphorus and sulphur. 15

The type of organic base composition contemplated for use in the reaction above described, by which the addition agents are produced, is represented by the following examples:

I. Hydrocarbons, preferably containing more than four (4) carbon atoms

A. Chain type (acyclic)

(1) Paraffins, e. g.

Pentane

Hexane

Octane

Decane

Acyclic terpenes

(2) Olefines, e. g.

Hexylene

Di-butylene

Di-iso-butylene

Amylene

(3) Acetylenes, e. g.

Butyne, crotonylene

Pentine, valerylene

Hexine, hexylene

Heptine, octanylene

Octine, caprylidene

Decine, menthene

Dodecylidene

B. Cyclic

(1) Cycloaliphatic, e. g.

(a) Naphthenes, e. g.

Cyclopentane

Cyclohexane

Cyclo octane

(b) Cyclo olefins, e. g.

Cyclobutene

Cyclopentene

Cyclohexene

(c) It will be noted that certain of the above, i. e., cyclo-

hexane and cyclohexene, are also hydro-aromatic

compounds, of which the following are additional

examples:

The hydro-diphenyls

The hydro-naphthalenes, e. g.,

Hexa- & dodeca-hydronaphthalenes

Tetra- & decahydronaphthalenes

The hydro-anthraces

The hydro-phenanthrenes

The hydro-retenes

(2) Aromatic, e. g.

Benzene

Di-phenyl

Naphthalene

Anthracene

Phenanthrene

Bridged ring hydrocarbons, e. g.

Aromatic terpenes such as pinene

Homologs of the above such as alkylated aro-

matic hydrocarbons, e. g. methyl, ethyl, propyl

and iso-propyl, butyl, amyl, etc. benzenes, di-

phenyls, naphthalenes, anthracenes, phenan-

threnes—more specific examples are toluene, xy-

lene, ethyl-benzene, cumene, cymene, methyl

naphthalene, retene

Aromatic hydrocarbons with one or more un-

saturated side-chains, such as phenyl ethylene

(styrene)

II. Naturally occurring, or commercially available complex com-

positions consisting principally of hydrocarbons

A. Petroleum and petroleum derivatives, such as crude mineral

oils of paraffinic, naphthenic, or asphaltic character and from various sources including the Penna., Mid-Cont., and Coastal fields; and products refined from them, e. g.

Bright stock

Neutral or pale oils

Steam refined oils

Fuel oils

Kerosene

Gas oils

Gasolines

Paraffin wax (or petroleum wax)

Petrolatum

Solvent extracted fractions, e. g.

Edelenam extract

Furfural extract

B. Hydrocarbon materials of non-mineral origin, e. g. hydro-

carbon products of vegetable origin such as certain oils obtained from the distillation of wood, etc., e. g.

III. Oxygen-bearing organic compounds (including oxygen-bearing derivatives of hydrocarbons in groups I and II above) may be classified according to the nature of attachment of the oxygen atom, viz:

(a) Directly attached to one or more carbon atoms, as in the case of:

(1) Ethers and analogous compounds,

(2) Compounds containing the $\text{O}-\text{OH}$ radicle, such as the alcohols and other derivatives of carbinol (including phenols, cresols, naphthols, etc.)

(3) Compounds containing the carbonyl $\text{C}=\text{O}$ radicle, such as amides, aldehydes, ketones, organic acids, esters and salts of organic acids, thio-acids and esters of thio-acids.

(4) Compounds in which oxygen forms a part of the ring structure, e. g., furan and its derivatives, etc.,

(5) Compounds with an inorganic radicle where the oxygen is directly attached to a carbon atom

Arsenite

H₃pochlorite

Phosphite

Thiophosphate

Thiophosphite

β -Hydroxylamines

(b) Indirectly attached through the means of some other atom i. e., in the form of an inorganic radicle, e. g.:

Arsenate

Chlorate

Chlorite

Cyanate

α -Hydroxylamine

Nitrate

Nitrite

Nitro

Perchlorate

Phosphate

Sulphate

Sulphite

Sulphinic acid

Sulphone

Sulphonic acid

Sulphoxide

Thio-sulphate

The following are specific examples of suitable oxygen-bearing compounds:

ALIPHATIC

AROMATIC

Alcohols

Methyl alcohol

Benzyl alcohol

Ethyl alcohol

Phenyl ethyl alcohol

Propyl and iso-propyl alcohols

Butyl and iso-butyl alcohols

Amyl alcohols

Lauryl alcohol

Cetyl alcohol

Polyhydroxy alcohols:

Dihydroxy alcohols, e. g.

Ethylene glycol

Di-ethylene glycol

Tri-hydroxy alcohols, e. g.

Glycerine

Phenols

Monohydroxy, e. g.

Phenol

Alkyl phenols, e. g.

Cresols

Xylenols

Ethyl phenols

Propyl & iso-propyl phenol

Amyl phenols

Phenyl phenols

Naphthols

Polyhydroxy, e. g.

Dihydroxy e. g.

Pyrocatechin (Catechol)

Resorcinol

Hydroquinone

Dihydroxy diphenyls

Tri-hydroxy, e. g.

Tri-hydroxy benzenes

Pyrogallol

Hydroxy-hydroqui-

none

Phloroglucinol

Others, e. g.

Rufigallol

Ethers

Di-ethyl ethers

Diphenyl ethers

Propyl and isopropyl ethers

Dixenyl ethers

Butyl and isobutyl ethers

Dinaphthyl ethers

Amyl ethers

Mixed ethers

Ethyl propyl ethers

Phenyl naphthyl ethers

Methyl butyl ethers

Phenyl ethyl ethers

Ethyl naphthyl ethers

Phenyl propyl ethers

ALIPHATIC	AROMATIC	Naturally occurring, or commercially available complex oxygen-bearing organic compositions such as:	
	<i>Hydroxy ethers</i>		
Glycol ether (diethylene-glycol)	Mono-methyl ethers of dihydroxy phenols, e. g.		Non-mineral oils and waxes, e. g.
Mono-alkyl esters of dihydric alcohols, e. g.	Methoxy phenols	5	Fatty oils, including:
Mono-methyl ester of ethylene glycol			Animal oils, Fish oils Lard oil Vegetable oils Cottonseed oil Rape seed oil Corn oil Castor oil Soya bean oil
	<i>Ketones</i>	10	Waxes of animal or vegetable origin: Carnauba wax Palm wax Beeswax Japan wax
Acetone	Benzophenone		
Di-ethyl ketone	Naphthyl ketones		
Di-propyl ketones			
	<i>Mixed ketones</i>		
Methyl-ethyl ketone	Acetophenone	15	Of the foregoing named organic base compositions, the following are among the more suitable:
Methyl propyl ketones	Ethyl phenyl ketone		Hydrocarbon materials
Ethyl propyl ketones, etc.	Mixed long chain aryl ketones, such as		Petroleum derivatives, particularly
	Dibenzofuryl heptadecyl ketone		Mineral oil, for example
	Dibenzofuryl undecyl ketone as described in U. S. Pat. No. 2,033,548	20	Bright stock (preferably Pennsylvania)
			Neutral or pale oils
	<i>Cyclo-ketones</i>		Oxygen-bearing organic compounds
Cyclohexanone	Quinone		Phenol
	Anthraquinone		Cresols
			Diphenyl ether
	<i>Aldehydes</i>	25	Stearic acid
Acetaldehyde	Benzaldehyde		Benzyl alcohol
Propyl aldehydes	Salicylaldehyde		Lauryl alcohol
	Naphthyl aldehydes		Oxidized hydrocarbons including oxidized mineral oils
			Naphthenic acid
	<i>Acids</i>	30	Methyl stearate
Fatty acids, e. g.	Monocarboxylic, e. g.		Butyl stearate
Saturated:	Benzoic		Methyl salicylate
Acetic	Phenyl acetic		Oleic acid
Propionic	Phenyl propionic		Fatty oils such as lard oil
Butyric	Phenyl acrylic (cinnamic)		Halogen-bearing organic compounds
Lauric	Salicylic		Mono- & dichlor xylene
Palmitic	Polycarboxylic, e. g.	35	Mono- & dichlor cresol
Stearic	Phthalic		Para- & orthochlorphenol
Unsaturated:	Hydroxy:		Monochlor pentane (chlor amyl phenol)
Oleic	Salicylic		Chlorinated diphenyl ether, for example
Hydroxy:			Trichlor diphenyl ether and
Lactic			Hexachlor diphenyl ether
Ricinoleic			Mono- & dichlor benzyl alcohol
			Methyl dichlor stearate
	<i>Esters</i>	40	The reagents which may be employed with the above defined organic base compositions in producing the so-called addition agents, according to this invention, are, as previously indicated, characterized by their containing free or combined phosphorus and sulphur, either present in the same or different compounds and either in elemental or combined form. Those containing the above-named elements in combined form may generally be classified as follows:
Esters of an aliphatic alcohol (such as those listed above under "Alcohols") and a fatty acid (such as those listed above under "Acids") e. g.	Esters of a phenol (such as those listed above under "Phenols") and a fatty acid (such as those listed above under "Acids") e. g.		
Methyl	Acetate	45	REAGENTS
Ethyl	Propionate		A. Phosphorus compounds
Propyl	Butyrate		1. Compounds of phosphorus and halogen
Butyl	Laurate		Phosphorus chloride— P_2Cl_5
Amyl	Palmitate		Phosphorus tri-chloride— PCl_3
Lauryl	Stearate		Phosphorus pentachloride— PCl_5
Cetyl	Oleate	50	Phosphorus diclor trifluoride— PCl_2F_3
Ethylene			2. Compounds of phosphorus and oxygen
Diethylene			Phosphorus trioxide— P_4O_6 (or P_2O_3)
Glyceryl			Phosphorus tetroxide— P_4O_10
	Esters of an aromatic alcohol (such as those listed above under "Alcohols") and a fatty acid (such as those listed above under "Acids") e. g.	55	Phosphorus pentoxide— P_2O_5 (or P_4O_10)
Benzyl and phenyl-ethyl	Acetate		3. Compounds of phosphorus, oxygen and halogen
	Propionate		Phosphorus oxychloride— $POCl_3$
	Butyrate		Phosphorus trioxotetrachloride— $P_2O_5Cl_4$
	Laurate		4. Elemental phosphorus
	Palmitate	60	1. Sulphur and halogen
	Stearate		Sulphur monochloride— S_2Cl_2
	Oleate		Sulphur trichloride— SCl_3
Esters of an aliphatic alcohol (such as those listed above under "Alcohols") and an aromatic acid (such as those listed above under "Acids") e. g.	Acetate	65	2. Sulphur and oxygen
Methyl	Propionate		Sulphur dioxide— SO_2
Ethyl	Butyrate		Sulphur trioxide— SO_3
Propyl	Laurate		Sulphur heptoxide— S_2O_7
Butyl	Palmitate		3. Sulphur, oxygen and halogen
Amyl	Stearate	70	Sulphur monooxytetrachloride— S_2OCl_4
Lauryl	Oleate		Sulphur pentoxydichloride— $S_2O_5Cl_2$
Cetyl			Sulphuric oxychloride— SO_2Cl_2
Ethylene			Sulphurous oxychloride— $SOCl_2$
Diethylene			4. Elemental sulphur
Glyceryl			1. Compounds of phosphorus and sulphur alone
	Benzoylate		Phosphorus disulfide— PS_2 (or PS)
	Phenyl acetate		Phosphorus trisulfide— PS_3 (or P_2S_3)
	Salicylate		Phosphorus sesquisulfide— PS_2
	Phthalate		Phosphorus pentasulfide— PS_5 (or P_4S_10)
			Phosphorus heptasulfide— PS_7
Esters of fatty acids derived from naturally occurring fatty oils and waxes, and of the hydrogenated acids derived from like sources, e. g.: Methyl, ethyl, butyl, etc. esters of coconut fatty acid, palm fatty acid, or the same after hydrogenation.		75	2. Compounds of phosphorus, sulphur and halogen
			Phosphorus trichloride— $PSCl_3$
			Phosphorus thibromide— $PSBr_3$
			Phosphorus thibromide— PS_2Br_4

3. Compounds of phosphorus, sulphur and oxygen
Phosphorus sulphoxide— $P_2S_4O_6$
4. Compounds of phosphorus, sulphur and elements other than oxygen or halogen
Phosphorus thiocyanate— $P(CNS)_3$
- D. Reagents containing elements equivalent to phosphorus and/or sulphur.
1. Compounds of phosphorus and equivalents of sulphur, e. g.
Se, for example
 P_2Se
 P_2Se_2
 P_2Se_3

It will be noted that since the so-called addition agent produced by the above referred to reaction shall contain both phosphorus and sulphur, and advantageously phosphorus, sulphur and oxygen, organic compounds and the reagents selected shall be such as to produce the addition agent of the desired character.

The following is a list of particularly suitable addition agents. Since the addition agents in the list are identified according to the organic compounds and reagents used in their preparation, it includes typical examples of suitable organic compounds and reagents.

- A. Reaction products of the following organic compounds with phosphorus pentasulphide (P_2S_5):
- Stearic acid
Lauryl alcohol
Benzyl alcohol
Phenol
Butyl stearate
Methyl salicylate
Naphthenic acid
Diphenyl ether
Cresyllic acid (cresol)
Mineral oils such as bright stocks and neutrals (preferably Penn.)
Oxidized mineral oils
Fatty oils such as lard oil
Chlorinated diphenyl ether, particularly
Trichlor diphenyl ether and
Hexachlor diphenyl ether
Mono- & dichlor benzyl alcohol
Para- & orthochlor phenol
- B. Reaction products of the following organic compounds with phosphorus sulphochloride (PCl_3)
- Mineral oils such as bright stocks and neutrals (preferably Penn.)
Oxidized mineral oils
Naphthenic acid
Methyl stearate
Fatty oils such as lard oil
Methyl salicylate
Stearic acid
Oleic acid
Diphenyl
Dichlor xylene
Dichlor cresol
Orthochlor phenol
Monochlor amyl phenol
Methyl dichlor stearate
Chlorodiphenyl
- C. The reaction products of thiophenol and chlorinated thiophenol with phosphorus trichloride
- D. The reaction products of thiophenol and chlorinated thiophenol with phosphorus oxychloride.
- E. The reaction products of chlorinated tricresyl phosphate (one or more chlorine atoms on one or more methyl groups) with sodium polysulphide.
- F. The product produced by reacting with phosphorus oxychloride ($POCl_3$)
- (a) The reaction product of phenol with phosphorus pentasulphide (P_2S_5) and
- (b) The reaction product of orthochlorophenol with phosphorus pentasulphide.

The foregoing typical examples will be sufficient for those skilled in the art in utilizing the named reagents as well as their equivalents in producing the addition agents of this invention.

The foregoing method of preparing the addition agent contemplated herein involved the use of reagents containing both phosphorus and sulphur or separate reagents which include both phosphorus and sulphur. Methods of preparing these addition agents other than that described above may be used, for example, by reaction of the following:

- A. Organic sulphur compounds with phosphorus-bearing reagents, e. g.
- (1) Mercaptans (including thio-alcohols and thio-phenols) with
(a) $POCl_3$
(b) PCl_3
(c) $PSCl_3$
(d) PaO_3
(e) PCl_4

- B. Organic phosphorus compounds with sulphur-bearing reagents, e. g.
- (1) Chlorinated organic phosphates or phosphites, (preferably with chlorine attached to aliphatic radicle) with
Inorganic sulphide or polysulphide
- (2) Organic phosphates and phosphites (preferably containing unsaturated organic radicles or products of incomplete reaction of organic hydroxy compounds with phosphorus-bearing reagents such as $POCl_3$ and PCl_3) with
(a) $SeCl_2$
(b) SCl_2
(c) Elemental sulphur

Certain of the addition agents themselves, which have been previously generically defined as organic compounds containing both phosphorus and sulphur, may be generically, subgenerically and specifically classified in the following manner:

- (1) Organic compounds containing both phosphorus and sulphur
(2) Organic compounds containing phosphorus, sulphur and oxygen
(3) Any of the foregoing compounds which contain a halogen.

A slightly different classification for certain types of the compounds usable as so-called addition agents, in accordance with this invention, is

- (1) Esters of phosphorus- and sulphur-containing acids, e. g.
Esters of tri-thiophosphorus acid and tetrathiophosphoric acid
- (2) Esters of phosphorus-, sulphur- and oxygen-containing acids, e. g.
Esters of thiophosphorus, thiophosphoric and tri-thiophosphoric acids
- (3) Any of the previously mentioned compounds which contain a halogen.

Among the specific examples of addition agents contemplated for use in accordance with this invention which have been previously somewhat more generically defined, the following compounds may be mentioned, viz:

- Tri-butyl thiophosphate
Tri-phenyl thiophosphate
Tri-benzyl thiophosphate
Tri-cresyl thiophosphates, e. g.
Tri-(ortho-cresyl) thiophosphate
Tri-butyl tri-thiophosphate
Tri-phenyl tri-thiophosphate
Tri-cresyl tri-thiophosphate
Tri-butyl tri-thiophosphate
Tri-phenyl tri-thiophosphate
Tri-cresyl tri-thiophosphate
Tri-(chlor ethyl) thiophosphate
Tri-(orthochlor phenyl) thiophosphate
Tri-(orthochlor phenyl) tri-thiophosphate
Tri-(dichlor xylil) thiophosphate
Tri-(dichlor cresyl) thiophosphate
Tri-(monochlor amyl phenyl) thiophosphate
Tri-(chlorbenzyl) thiophosphate
Tri-benzyl tri-thiophosphate
Tri-lauryl tri-thiophosphate
Tri-(orthochlor phenyl) tri-thiophosphate

As previously indicated, the above named addition agents are usable either by themselves as lubricants or advantageously in small amounts as addition agents to other lubricating compositions. Their particular effectiveness in very small amounts for the purposes previously specified and hereafter explained in greater detail makes the so-called addition agents especially desirable for use in lubricating compositions comprising any of the well known oils usually used as lubricants, such as mineral oil, non-mineral oils such as animal and vegetable oils e. g. rape-seed oil, castor oil, or, for certain uses, desirable combinations of such oils.

It has been found that when a refined mineral lubricating oil base is used, the previously named desirable properties may be imparted thereto by the use of the named addition agents in amounts upwards of 0.10%. The amount of addition agent used in excess of the stated minimum depends of course upon the particular use for which the resultant composition is designed; in preparing a lubricant for use in the crank case of internal combustion engines, the composition will be found to give superior results if it contains from about 0.10% to about 2% of the addition agents.

If the resultant composition is to be used under

conditions of higher pressure where generally temperatures lower than those in a crank case are encountered, for example in lubricating heavily loaded gears and bearings, the addition agent may be present in greater amounts, i. e., up to 5 and, in certain cases, desirably up to 10 and 20% may be employed.

The principal advantages resulting from the use of the named addition agents in lubricating compositions of the character described are as follows: The addition agents will be found to impart substantial extreme pressure characteristics to the lubricants. The addition agents containing phosphorus, sulphur, halogen and oxygen will be found, in general, to be more effective than those containing only phosphorus, sulphur and oxygen, and the latter will generally be found to be more effective as extreme pressure addition agents than those which contain only phosphorus and sulphur.

Certain of the addition agents have an inherent property of inhibiting corrosion of metallic surfaces by such constituents as are usually present either by virtue of being contained in the mineral oil, created in the mineral oil during the refining process, or intentionally added thereto for the purpose of producing a particular result. Certain of the addition agents of this invention have the remarkable combination of properties which make it possible to increase the film strength of a mineral lubricating oil by the addition of very small percentages while, at the same time, improving the stability of the lubricant and maintaining it free from harmful corrosive action. This combination of properties is particularly associated with aromatic esters of thiophosphorus acids which contain a halogen, specifically chlorine, in such form that it is directly attached to a carbon atom which is part of an aromatic ring. While halogen in this form is particularly stable, and ordinarily increases the film strength to only a moderate degree, the addition of halogen in such form with an aromatic ester of thiophosphorus acid increases the film strength to a very great extent much in excess of the degree to be expected from a comparison with other aromatic halogen compounds of the type in which the halogen is directly attached to an aromatic ring.

The oiliness factor of a lubricant, to which certain of the named addition agents have been added, has been found to be measurably improved over similar untreated lubricating compositions with which they have been compared.

The tendency of the lubricating composition to form sludges resulting either from oxidation on standing or under conditions of use is generally considerably reduced by the presence therein of the addition agent. If any sludge constituents are formed in the lubricating composition containing the addition agents, the latter have a marked tendency to render harmless such constituents so that even so formed, their presence in the composition is not objectionable.

Certain of the named constituents have been found to very materially improve the viscosity index and cold test characteristics of mineral lubricating oils to which they have been added.

The stability and volatility of the addition agents should be such that under conditions encountered in service the concentration of the addition agent in the lubricant will not be substantially reduced because of its loss by evaporation or by decomposition.

For most uses the addition agent should have a vapor pressure less than atmospheric at a tem- 75

perature of 140° C.; and if the lubricant is to be subjected to elevated temperatures in use, less than atmospheric at 170° C.

The stability of the addition agent should be such that decomposition shall be negligible at temperatures to which the lubricant will be exposed in service.

By the term "non-corrosive" as used herein and in the appended claims is meant such forms of the addition agents as will not react chemically to a substantial and continuing extent with the bearings and other metallic parts exposed to the lubricant excepting under conditions of extreme pressure and the like, nor cause damaging corrosion of such metallic parts.

The foregoing statements as to non-corrosiveness, stability and volatility of the addition agents applies particularly to compositions made in accordance with this invention and used as lubricants and especially when such lubricants are employed under conditions of extreme stress such as imposed by high temperature, extremely high pressure and the like. There are, however, certain uses such as in metal working, die drawing and the like where relatively more active, i. e., relatively corrosive, addition agents of the character referred to herein may be employed to advantage.

While the lubricating compositions which have been described herein as illustrating one embodiment of the invention have been generally referred to as "oils," i. e., liquids, this invention is, however, also applicable to the solid and semi-solid types of lubricants commonly referred to in the trade as greases, bodied oils, etc. In this connection, it should be noted that certain of the addition agents contemplated for use herein for the purpose of imparting extreme pressure characteristics to the lubricant may be employed for the additional purpose of bodying or thickening the lubricant to which they are added.

Other modes of applying the principle of my invention may be employed instead of the one explained, change being made as regards the materials employed in carrying out the process, provided the ingredient or ingredients stated in any of the following claims or the equivalent of such stated ingredient or ingredients be employed.

I, therefore, particularly point out and distinctly claim as my invention:

1. A lubricating composition comprising an organic compound containing phosphorus, sulfur and halogen.
2. A lubricating composition comprising an organic compound containing phosphorus, sulfur, oxygen and halogen.
3. A lubricating composition comprising a major proportion of mineral oil and a minor amount of an organic compound containing phosphorus, sulfur and halogen.
4. A lubricating composition comprising a major proportion of mineral oil and a minor amount of an organic compound containing phosphorus, sulfur and chlorine.
5. A lubricating composition comprising a major proportion of mineral oil and a minor amount of an organic compound containing phosphorus, sulfur, oxygen and halogen.
6. A lubricating composition comprising a major proportion of mineral oil and a minor amount of an organic compound containing phosphorus, sulfur, oxygen and chlorine.
7. A lubricating composition comprising a

major proportion of mineral oil and a minor amount of a halogenated organic thiophosphate.

8. A lubricating composition comprising a major proportion of mineral oil and a minor amount of a halogenated organic thiophosphate.

9. A lubricating composition comprising a major proportion of mineral oil and a minor amount of an organic compound containing phosphorus, sulfur and halogen in which at least a portion of the halogen is attached to a carbon atom of an aromatic ring. 10

10. A lubricating composition comprising a major proportion of mineral oil and a minor amount of an organic compound containing phosphorus, sulfur and halogen in which all of the halogen is attached to a carbon atom of an aromatic ring.

11. A lubricating composition comprising a major proportion of mineral oil and a minor amount of tri-(dichlor xylyl) thiophosphate.

CARL F. PRUTTON.
